UNITED STATES PATENT OFFICE.

FRANK E. ROBERTSON, OF CLEVELAND, OHIO, ASSIGNOR TO THE P. A. GEIER COMPANY, OF CLEVELAND, OHIO, A CORPORATION OF OHIO.

MECHANISM FOR POWER-DRIVEN WASHING MACHINES.

Application filed July 25, 1918. Serial No. 246,653.

To all whom it may concern:

Be it known that I, FRANK E. ROBERTSON, a citizen of the United States of America, residing at Cleveland, in the county of 5 Cuyahoga and State of Ohio, have invented certain new and useful Improvements in Mechanism for Power-Driven Washing Machines, of which the following is a specification.

10 My invention relates to improvements in power-driven washing machines and the like, and more particularly to machines which are adapted to impart reciprocatory motion, such as the pounder type of washing machine; preferably operated by an electric motor mounted in unitary, compact relation with the transmitting mechanism.

15 The objects of my invention are the simplification, condensation and cheapening of 20 this class of machines, through the mechanical and electrical features hereinafter explained in detail and set forth in the appended claims.

I may first describe in outline, the embodiment of my invention about to be explained in detail and made the subject of more general claims. As herein applied, the 25 operating mechanism is comprised in a unit which is adapted alternatively to operate 30 the pounder mechanism or a clothes wringer; being controlled for this purpose by a suitable clutch. The upper portion of the casing comprises an electric motor of relatively slow speed and preferably of some approved 35 universal type, which is electrically insulated from the casing and operating mechanism.

The operating mechanism includes an insulating gear wheel at the upper end of an 40 angularly inclined screw shaft, which in turn drives a power shaft mounting the clutch. The gear wheel upon said shaft is slightly offset axially of the motor and casing, in order to afford a more compact arrangement of the parts. The angularly inclined driving shaft is provided with ball-retaining members above and below for the ball-bearings thereof and the eccentric actuating the reciprocating mechanism also 45 may be provided with balls and ball-races for reducing friction, as may the motor 50 bearings, if desired.

It is particularly desirable with the

pounder type of washing machines, to have the pounder mechanism supported out of 55 the way and in elevated position when not in use, and I have provided mechanism associated with the clutch for disconnecting the same operatively only at the point of maximum elevation of the pounder mechanism, 60 while automatically throwing into service the supporting member. These with further details of construction and advantage will now be explained in connection with the 65 accompanying drawings, wherein:—

Fig. 1 is an enlarged fragmentary section of the lower portion of the operating mechanism.

Fig. 2 is a similar view thereof; the section being taken at right angles to that of 70 Fig. 1.

Fig. 3 is a view in elevation of the wringer mechanism from which the operating mechanism has been removed.

Fig. 4 is a front view of the assembled 75 mechanism; the same being shown partly in section.

Fig. 5 is a fragmentary detail partly in section, showing the transmitting mechanism.

Fig. 6 is a similar view thereof; the section being taken at right angles to that of Fig. 5, and

Figs. 7 and 8 are fragmentary views illustrating the adjustable drip board of the 85 wringer, with its attachments.

Throughout the several figures of the drawings I have employed the same character of reference to indicate similar parts.

As indicated, with this class of washing 90 machine, which is adapted readily to be attached to and removed from a stationary tub, it is desirable not only that the motor shall operate the wringer as well as the washer, but it is convenient to attach the 95 operating mechanism as a unit to the wringer structure itself, as shown in the drawings. The wringer *a* is removably attached by the clamps *a'* preferably to a resilient wooden strip *a''* mounted at the 100 edge of the stationary tub. There is bolted to the wringer frame, a compact casing *c* axially mounting the electric motor *b* in insulating relation at the top thereof. In 105 order to provide a compact rigid worm-drive for the motor, an inclined, though substan-

tially vertical shaft d provided near its upper end with a gear wheel d' and at its lower end with a worm or screw d'' , is interposed between the motor and the power shaft e . The motor is provided with a co-acting gear wheel b' , preferably of bakelite or other suitable fiber insulating material, the teeth of which are cut at an angle corresponding with the incline of shaft d to permit the offset compact disposition of the gear wheel e' on shaft e , with which the clutch member e'' rotates in splined relation. This clutch member has three positions controllable by the lever f and its connecting rod f' . As best shown in Fig. 2, the arm g engages with the groove in clutch member e'' at its lower forked end and effects its limited lateral movement upon the power shaft e . Adjustably connected with this arm g by means of the screw i' is the supporting member i ; both being afforded a limited lateral movement upon the rod i'' in the upper portion of casing c . As best shown in Figs. 1 and 5, the 25 pounder mechanism (not shown itself, being of the desired type and not a part of my invention) is adapted to be supported and actuated by the parallel pivoted arms h h' ; the former being connected with the ball-bearing eccentric j sleeved upon shaft e and having a member j' for engagement with the rotated clutch member e'' splined upon the power shaft e . A corresponding member k' is oppositely positioned upon the shaft of 30 the wringer roll k . By this compact arrangement of parts and transmission mechanism, it is seen that the power from the motor at considerably diminished speed may alternatively be applied either to the reciprocating mechanism or to the wringer, while a median position of the clutch member e'' will disconnect both appliances from the source of power.

Since it is desirable with washing machines, and indeed with other reciprocating mechanisms, to support or lock the same in predetermined position, as the elevated position of the pounder mechanism for washing machines, I will now explain the automatic 45 means for effecting the latter result. Upon referring to Figs. 2 and 6, it will be observed that the travel of supporting member i brings it immediately above the rear end of lever arm h , when said end is depressed, and in consequence, the outer end of said lever arm, normally carrying the pounder mechanism, is in its position of maximum elevation. However, member i may not be moved to the left into this supporting position for the lever arm and any connected mechanism thereon, until the rear end has reached its depressed position, for the reason that it will be in the way at other times and thus effectually obstruct its movement. For the same reason, the clutch mem-

ber e'' may not be disengaged from its co-acting member j' , except at the point of maximum elevation of the lever arm h , since members g and i are connected and move together along rod i'' . When this relation of the parts exists, the clutch may be disconnected and supporting member i will retain the arm h in its elevated position, as best shown in Fig. 1, as long as the wringer mechanism is driven by the motor, or the 75 clutch member remains in its median position.

In order that the wringer mechanism may operate equally well from either side, an adjustable drip board l having a notch l' , is 80 adapted to be inclined and locked either at one side or the other, by the latches l'' , so that said drip board may drain in either direction, as desired.

Preferably in connecting the electric motor, it is grounded with its frame connected to the plumbing fixtures, and as shown, said motor is fully insulated with respect to the casing and by means of the fiber gear wheel, 90 so that all danger from electrical shock is avoided.

These, and other details herein described, form no part of my present invention, as claimed below, and it should be understood that material departures from the precise construction described may be made without departing from my invention, except as I have expressly claimed the same.

Provided with the preferred clutch and supporting mechanism for the lever arms, as 100 it is, my improved washing machine may be disconnected only at the top of the up-stroke; in which position the mechanism is automatically locked.

The extremely compact and efficient transmission mechanism, mounted as a unit, including the inclined shaft with attached ball-bearing cases, constitute important features of improvement. These operate quietly in a grease-filled casing, and in either direction, as required for the wringer.

Having now described the preferred embodiment of my invention, I claim as new and desire to secure by Letters Patent, together with such modifications as may be made by mere skill, the following:

1. In a mechanism for power-driven machines, the combination with a reciprocatory mechanism, of an electric motor associated therewith, an intermediate driving mechanism, a clutch for connecting and disconnecting the same, shifting means for the clutch, and a combined adjustable support and blocking member adapted to block said shifting means except when the reciprocatory mechanism is in a predetermined position, substantially as set forth.

2. In a mechanism for power-driven machines, the combination with a power device, of a reciprocatory working member, me- 130

chanically connecting means including a clutch, and mechanism preventing the actuation of the clutch except when the working member is in a predetermined position 5 or alternatively supporting said working members, substantially as set forth.

3. In a transmitting mechanism for power-driven machines of the class described, the combination with an electric motor axially 10 positioned with respect to said mechanism, of a gear wheel having its teeth cut at an angle with the axis of the motor, a power transmitting shaft, a gear wheel thereon, and a shaft positioned at an angle 15 with the axis of the motor, having respectively a gear and worm for engaging said gear wheels to transmit power from the motor, substantially as set forth.

4. In a transmitting mechanism for power-driven machines of the class described, the combination with a casing, of an electric motor axially positioned in line with the axis of the casing, an associated gear wheel having angularly cut teeth, a power transmitting shaft extending transversely to the axis of the casing and motor, a gear wheel offset thereon, a connecting shaft positioned at an angle to the axis of the casing and motor, having respectively a gear and a 25 screw for engaging said gear wheels to transmit power from the motor to the transverse shaft, substantially as set forth.

5. In a transmitting mechanism for power-driven machines of the class described, the combination with a casing mounting the 30 several members as a unit, including an electric motor having its axis parallel with the axis of the casing, a transmitting gear wheel with its teeth cut at an angle with the axis, a transmitting shaft mounted in ball-bearings at a corresponding angle to the axis, a power shaft positioned within the casing transversely of the axis, and means connecting the two shafts, substantially as set forth.

6. A unitary transmission of the class described, comprising a casing, a motor device centered within the casing, a transverse power shaft, an offset gear wheel thereon, 35 and connecting mechanism including a worm taking with said gear wheel, an inclined shaft driving the worm, and a gear wheel with teeth inclined at the same angle as said shaft, substantially as set forth.

55 7. In a mechanism for intermittently driven machines, the combination with a reciprocating part, of a power device for actuating the same, and driving mechanism connecting said elements, associated with a clutch and supporting means for said reciprocating part adapted alternatively for

preventing the disconnection of the clutch except in a predetermined position of the reciprocating part, substantially as set forth.

8. In mechanism of the class described, 65 the combination with a motor device, of a lever arm pivoted to be reciprocated thereby, mechanically connected driving means interposed therebetween, including a clutch and a connected supporting member for said lever arm adapted concurrently to be actuated when the lever is in a definite position only, substantially as set forth.

9. In mechanism of the class described, 70 the combination with a reciprocated member, of a supporting device and a connected clutch adapted concurrently to be actuated, alternatively to release and connect said member for actuation, or to disconnect and support said member in a determined position, substantially as set forth.

10. In controlling mechanism of the class described, the combination with a pivoted reciprocated lever, of a power-driven shaft associated therewith for its actuation, a 75 clutch device, and a blocking member and support connected therewith and alternatively adapted to prevent the disengagement of the clutch or support the lever in a predetermined position, substantially as set 90 forth.

11. In controlling mechanism for washing machines and the like, the combination with an actuated reciprocating arm, of a power-driven shaft adapted for connection 95 therewith, a three-position clutch for effecting such connection and a combined supporting and blocking member controlling the clutch and engaging said arm, adapted alternatively to support the arm in two positions of the clutch or prevent the disengagement of the clutch except during the maximum elevation of said reciprocating arm, substantially as set forth.

12. In an attachable washing machine 100 mechanism, the combination with an electric motor, of a power-shaft, worm and gear connection between said motor and shaft, a pivoted reciprocating lever connected for actuation by the shaft, a connecting clutch device, and a combined blocking member and support associated therewith and alternatively adapted to prevent the disengagement of the clutch or support the lever in its elevated position, substantially as set 115 forth.

In testimony whereof I hereto affix my signature in the presence of two witnesses.
